(57) **CLAIM**

The ornamental design for a hair twist with feather, as shown and described.

DESCRIPTION

FIG. 1 is an front, right perspective view of a first embodiment of a hair twist with feather showing my new design;
FIG. 2 is a front view of the first embodiment;
FIG. 3 is a rear view of the first embodiment;
FIG. 4 is a right side view of the first embodiment;
FIG. 5 is a left side view of the first embodiment;
FIG. 6 is a top view of the first embodiment;
FIG. 7 is a bottom view of the first embodiment;
FIG. 8 is front, right perspective view of a second embodiment of a hair twist with feather showing my new design;
FIG. 9 is a front view of the second embodiment;
FIG. 10 is a rear view of the second embodiment;
FIG. 11 is a right side view of the second embodiment;
FIG. 12 is a left side view of the second embodiment;
FIG. 13 is a top view of the second embodiment;
FIG. 14 is a bottom view of the second embodiment;
FIG. 15 is front, right perspective view of a third embodiment of a hair twist with feather showing my new design;
FIG. 16 is a front view of the third embodiment;
FIG. 17 is a rear view of the third embodiment;
FIG. 18 is a right side view of the third embodiment;
FIG. 19 is a left side view of the third embodiment;
FIG. 20 is a top view of the third embodiment; and,
FIG. 21 is a bottom view of the third embodiment.
The broken line showing of the environment is for illustrative purposes only and forms no part of the claimed design.
